DESIGN FOR AN ENDPiece FOR METALLIC SPECTACLE FRAMES

Charles J. Eagle, Rochester, N. Y.

Application November 4, 1935, Serial No. 59,371

Term of patent 3½ years

To all whom it may concern:

Be it known that I, Charles J. Eagle, a citizen of the United States, residing at Rochester, in the county of Monroe and State of New York, have invented a new, original, and ornamental Design for an Endpiece for Metallic Spectacle Frames, of which the following is a specification, reference being had to the accompanying drawing, forming a part thereof.

Figure 1 is a front elevation of the endpiece for metallic spectacle frames, showing my new design.

Figure 2 is a top plan view of the same.

Figure 3 is a side elevation of the same.

Figure 4 is an enlarged perspective view of the same.

The dominant feature of this invention resides in the formation of the endpiece in two sections which abut each other substantially the full length thereof and have long and narrow parallel outer ends terminating in short outflaring inner ends.

I claim:

The ornamental design for an endpiece for metallic spectacle frames, as described and shown.

CHARLES J. EAGLE.
